UNITED STATES PATENT OFFICE.

JOSEPH BARNETT, OF NEW YORK, N. Y.

FIRE-ESCAPE LADDER.

SPECIFICATION forming part of Letters Patent No. 312,793, dated February 24, 1885.

Application filed September 1, 1884. (No model.)

To all whom it may concern:

Be it known that I, JOSEPH BARNETT, of the city, county, and State of New York, have invented certain new and useful Improvements 5 in Fire-Escape Ladders, of which the following is a full, clear, and exact description.

Reference is to be had to the accompanying drawings, forming part of this specification, in which similar letters of reference indicate corresponding parts in all the figures.

Figure 1 is a plan view of my improved ladder shown lowered for transportation. Fig. 2 is a side elevation of the same, part being broken away. Fig. 3 is a front elevation of 15 the same. Fig. 4 is a side elevation of the turn-table and its standards, and showing the lower part of the ladder in a raised position. Figs. 5 and 6 are plan views of two of the connecting-plates.

20 The object of this invention is to provide fire-escape ladders constructed in such a manner that they can be readily raised for use and lowered for transportation, will be securely held when raised, and can be readily adjusted at different inclinations.

25 The invention consists in a fire-escape ladder constructed with a base-frame provided with a turn-table carrying standards and a hinged ladder, the said standards and ladder 30 being connected by a windlass, guide-pulleys, and rope or chain.

To the standards attached to the turn-table 35 is attached a cross-bar to receive connecting-plates hinged to the ladder, whereby the said ladder, when raised, can be firmly secured in place. The windlass journaled to the standards attached to the turn-table is provided with a brake, whereby the said ladder can be readily and quickly lowered. The turn-table 40 is provided with a hinged hook to engage with perforations in the base-frame, and hold the said ladder from lateral movement when adjusted. The ladder is strengthened by studs attached to its side bars and connected by rods and braces. The middle parts of the 45 lower rounds of the ladder can be cut away and bars attached to the inner ends of the said rounds, to allow the ladder, when lowered, to be moved forward, and thus better balanced 50 for transportation, as will be hereinafter fully described.

A represents the base-frame or platform,

which is mounted upon a running-gearing, B, in the manner of an ordinary wagon. C is a circular plate or turn-table, which rests in a 55 rabbed circular opening in the forward part of the base-frame A, and is pivoted to the center of a cross-bar, D, attached to the lower side of the said base-frame A.

To the turn-table C, upon the opposite sides 60 of its center and near its edges, are attached lugs E, to which are hinged the lower ends of the side bars of a ladder, F, by a rod, G, passed through the said lugs and ends.

To the turn-table C, in front of and at a little 65 distance from the center of the lower end of the ladder F, are bolted or otherwise secured the lower ends of two parallel standards, H, which may be made in one piece, if desired. The upper ends of the standards H are curved forward, and to and between the said standards, 70 at their upper ends and at the lower ends of their bends, are pivoted guide-pulleys I.

To the lower parts of the standards H is journaled a windlass, J, to which is attached 75 the end of a rope or chain, K. The rope or chain K passes around the pulleys I, and its other end is attached to a cross-bar, L, the ends of which are attached to the upper ends of the upper pair of studs, M, attached to the 80 side bars of the ladder F. The upper ends of all the studs M on each side are connected by a rod, N, the ends of which are inclined downward, and are attached to the side bars of the ladder. The ladder F can be further 85 strengthened by brace-rods O, attached to the studs M, the rods N, and the side bars of the said ladder. The windlass J is provided with a ratchet-wheel, P, and a pawl, Q, for holding the said windlass from turning back should 90 the crank be accidentally released, the said pawl being thrown back when the windlass is reversed to lower the ladder. The windlass J is also provided with a brake-strap, R, passing around the end of its drum, or the edge 95 of one of its drum-flanges, and connected with a foot-lever, S, as with a hand-lever, so that the operator can control the descent of the ladder. The standards H are strengthened against the rearward strain in raising and lowering the ladder F by braces T, attached to the said standards and to the rear part of the turn-table C.

To the rear part of the base-frame A are at-

tached the lower ends of one or more standards, U, to the upper ends of which is attached a cross-bar, V, to receive the ladder F when lowered. The ends of the cross-bar V are bent 5 upward to prevent the ladder F from slipping off the said bar while being carried.

To the projecting lower ends of the brace-
rods O, or to other supports attached to the
ladder F, are hinged one or more plates, W,
10 in the lower ends of which are formed holes
to receive the ends of a cross-bar, X, attached
to the upper parts of the standards H, and
which are secured in place upon the said ends
by pins Y. Several connecting-plates W of
15 different lengths, as shown in Figs. 5 and 6, are
designed to be connected with the ladder F,
so that the said ladder can be secured at different
inclinations.

To the rear part of the turn-table C is hinged
20 a bent catch rod or hook, Z, which, when the
said turn-table has been turned to bring the
ladder F into the desired position, drops into a
hole, a, in the base-frame A, and holds the
said ladder from turning when in use. The
25 middle parts of the lower rounds of the lad-
der F can be cut away and the inner ends of
the said rounds attached to two bars, b, as
shown in Fig. 1, so that the said ladder, when
lowered, can be disconnected from the lugs E,
30 and then moved forward, the bars b passing
upon the opposite sides of the standards H, to
better balance the said ladder for transporta-
tion.

The bars b may, if desired, be made in one
35 piece bent into U shape, as shown in Fig. 1.

Having thus described my invention, what I
claim as new, and desire to secure by Letters
Patent, is—

1. In a fire-escape ladder, the combination,
40 with a base-frame, a turn-table, and a ladder

hinged to said turn-table, of standards secured
to the turn-table, a windlass and rope for rais-
ing and lowering the ladder, a catch on the
turn-table engaging the base-frame for lock-
ing the turn-table in position, and catch-plates 45
on the ladder engaging the standards for hold-
ing the ladder elevated, substantially as herein
shown and described.

2. In a fire-escape ladder, the combination,
with the standards H, attached to the turn-
table, and the ladder F, hinged to the said
turn-table, of the cross-bar X, and the hinged
50 catch-plates W, substantially as herein shown
and described, whereby the said ladder, when
raised, can be firmly secured in place, as set
forth.

3. In a fire-escape ladder, the combination,
with the turn-table C, the hinged ladder F,
and means for locking the turn-table in posi-
tion, of the standards H, the guide-pulleys I, 60
the windlass J, the cross-bar X, and the hinged
plates W, substantially as herein shown and
described.

4. In a fire-escape ladder, the combination,
with the standards H, the hinged ladder F, 65
the rope or chain K, and the windlass J, of the
brake R S, substantially as herein shown and
described, whereby the said ladder can be
readily and quickly lowered, as set forth.

5. In a fire-escape ladder, the combination,
70 with the lower rounds of the ladder F, having
their middle parts cut away, of the bars b, sub-
stantially as herein shown and described,
whereby the ladder, when lowered, can be
moved forward and better balanced for trans- 75
portation, as set forth.

JOSEPH BARNETT.
